UNITED STATES PATENT OFFICE

168,833

HYDRAULIC RELIEF VALVE

William E. Eschliman, Columbus, Ohio, assignor
to The Denison Engineering Company, Colum-
bus, Ohio

Application May 28, 1952, Serial No. 19,931

Term of patent 14 years

(Cl. D78—1)

To all whom it may concern:

Be it known that I, William E. Eschliman, a citizen of the United States, residing at Columbus, in the county of Franklin, State of Ohio, have invented a new, original, and ornamental Design for a Hydraulic Relief Valve, of which the following is a specification, reference being had to the accompanying drawings forming a part thereof, in which

Fig. 1 is a perspective view of a hydraulic relief valve showing my new design.

Fig. 2 is a similar view of the rear portion of the valve shown in Fig. 1.

Fig. 3 is a plan view of the valve and Fig. 4 is a side elevational view of the valve shown in the other figures.

I claim:

The ornamental design for a hydraulic relief valve, substantially as shown.

WILLIAM E. ESCHLIMAN.
